 BOLT ACTUATOR.
 W. F. GILBERT.
 PATENTED AUG. 16, 1904.
 NO. 767,400.

UNITED STATES PATENT OFFICE.

WILBUR F. GILBERT, OF NEW BRITAIN, CONNECTICUT, ASSIGNOR TO
P. & F. CORBIN, OF NEW BRITAIN, CONNECTICUT, A CORPORATION
OF CONNECTICUT.

BOLT-ACTUATOR.

SPECIFICATION forming part of Letters Patent No. 767,400, dated August 16, 1904.

Application filed May 12, 1904. Serial No. 207,607. (No model.)

To all whom it may concern:

Be it known that I, WILBUR F. GILBERT, a citizen of the United States of America, residing at New Britain, in the county of Hartford and State of Connecticut, have invented certain new and useful Improvements in Bolt-Actuators, of which the following is a specification.

The object of my invention is to provide a device of the class specified having features of novelty and advantage.

Referring to the drawings, Figure 1 is a front view of the device. Fig. 2 is a sectional view on the line 2 2 of Fig. 1.

This device comprises a slotted face-plate on the rear surface of which locking-notches are formed. A spring whose ends are adapted to co-operate with said locking-notches is carried by the knob-shank, which works in the slot in the plate. On the inner end of the knob-shank a socket is formed to receive the bolt.

In the specific form of the device shown in the drawings there is a face-plate *a*, slotted as at *b*. A "back plate" *c*, having grooves *c' c'* at its ends, is secured to the rear surface of the face-plate, having a slot *c²* located between the grooved ends of said plate. The shank *d'* of the knob *d* passes through these slots and is secured to a flat spring *e*, which extends on each side of said shank in such a manner that

at either limit of the movement of the bolt one end of the spring is in engagement with one of the grooves. The ends of the spring are formed with projecting ribs *e'*, which interlock with the grooves in the back plate. Secured to the knob-shank back of the spring is a socket member *f*, which receives the bolt *g*.

I claim as my invention—

1. A bolt-actuator comprising a slotted face-plate having notches on its rear surface, a knob having a shank working in said slot, a spring secured to the said shank and adapted to interlock with the notches on the rear surface of the face-plate, and a bolt carried by said knob-shank.

2. A bolt-actuator comprising the bolt, a slotted face-plate, a slotted "back plate" secured to the rear surface of the face-plate and having locking-grooves formed at each end of said slot, a flat spring adapted to interlock with said locking-grooves, and a knob having a shank working in the slots in said face-plate and said "back plate," and secured to said spring and to the bolt.

In testimony whereof I affix my signature in presence of two witnesses.

WILBUR F. GILBERT.

Witnesses:

G. ERNEST ROOT,
THOMAS S. HOWARTH.
